UNITED STATES PATENT OFFICE.

LAMBERT L. RAYMOND, OF MINNEAPOLIS, MINNESOTA, ASSIGNOR TO BRODERICK-SON-RAYMOND CO., OF MINNEAPOLIS, MINNESOTA, A CORPORATION OF MINNESOTA.

LAMP SOCKET WITH LEADS ON SIDE.

Application filed October 26, 1925. Serial No. 64,838.

This invention relates to a light fixture or lighting device and while the invention is capable of various applications, it preferably is designed for use with a small decorative lighting device, such as a Christmas tree, lamp set, or lamp socket. As is well known, electric lamp sets for Christmas trees are now very extensively used. With these sets of the prior art small lamp sockets are used in which the two conductors extend through the end of the socket. With this arrangement, if the lamp socket depends from the conductors the axis of the socket is vertical, or the open end is directed downwardly. It is now a very common practice to use reflectors on the lamp sockets, which reflectors are disposed in a plane substantially at right angles to the axis of the socket. The sockets therefore have heretofore had to be wired or fastened in some manner so that the axes thereof would be horizontal if it was desired to have reflectors disposed vertical, which is particularly desirable. With the conductors coming out of the rear end of the socket the same were very apt to be pulled loose when it was attempted to twist the conductors around a twig or on some fastening means to properly dispose the sockets. On account of the position of the sockets having the conductors projecting through the ends it has not been possible to have a lamp depending into an open space in the tree and still be in proper position to support a reflector.

It is an object of this invention, therefore, to provide a lighting device comprising a lamp socket with the conductors so arranged that when the socket is suspended by the conductors it will have its axis in a substantial horizontal line.

It is a further object of the invention to provide a lighting device comprising a lamp socket having tip and shell conductors, one of which projects through the side of the socket or in a direction transversely of the axis of the socket.

It is a further object of the invention to provide a light fixture comprising a lamp socket having a shell therefor with a tip contact and conductors secured, respectively to said shell and tip contact which

project through a casing of said socket in a direction transversely of the axis of said socket.

It is more specifically an object of the invention to provide a lighting fixture comprising a lamp socket having a shell and a tip contact, together with a casing surrounding said shell with conductors secured to said tip and shell extending through said casing transversely of the axis of said shell and inclined slightly in a direction toward the open end of said shell.

These and other objects and advantages of the invention will be fully set forth in the accompanying drawings in which like reference characters refer to the same parts through the different views, and in which,

Fig. 1 is a view in side elevation of a limb, such as the limb of a Christmas tree;

Fig. 2 is a central longitudinal section through the lamp socket used; and

Fig. 3 is a vertical section taken on the line 3—3 of Fig. 2, as indicated by the arrows.

Referring to the drawings, a lighting fixture or device is shown comprising a metallic shell 4 having threads 4^a formed therein adapted to have an electric lamp screwed thereinto. The open end of the shell is shown as having a flaring rim 4^b. The rear of the shell carries an insulating plate 5 in which is secured a metallic tip contact 6 adapted to be engaged by the tip contact on the lamp. The shell 4, with the parts 5 and 6 carried thereby, is snugly fitted in a casing 7. This casing may be of any suitable insulating material, such as hard rubber or some artificial resin or other suitable substance. While the casing 7 may be of various forms, in the embodiment of the invention illustrated, the same is shown as of frusto-conical shape having a thickened bead or rim 7^a at its front end and a ridge or thickened portion 7^b at one side thereof.

A conductor 8 comprising a wire with an insulating coating thereon extends through an opening 7^c in the casing 7 and portion 7^b, which opening is inclined slightly forward toward the open end of the casing and said conductor is connected to the shell 4, preferably in the rear of the flaring

flange 4^b, as shown. Another conductor 9, also illustrated as an insulated wire, extends through an opening 7^d in casing 7 and portion 7^b, which opening also extends in an 5 inclined direction toward the open end of the casing and is connected at its inner end to the tip contact 6. In the embodiment of the invention illustrated considerable space is shown in casing 7 in the rear of shell 4 but it will be understood that this 10 space may be varied, as desired. Means such as a small eyelet or collar 13 may be placed on the conductor 19 adjacent the point where it is connected to the tip contact 6 so that when said conductor is pulled through the opening 7^d the member 13 will contact the inside of the socket and prevent tension being applied to the tip connection. Conductors 8 and 9 are connected 15 to the conductors forming a cord 10 and there will, as usual, be a series of lamp sockets connected to this cord.

In operation, the cord 10 having the conductors 8 and 9 and the lamp sockets thereon will be disposed about the Christmas tree so as to extend to various parts thereof, it being understood that, as usual, the cord 10 will have a plug secured thereto adapted 20 to be connected to a standard socket for supplying current.

As shown in Fig. 1, the cord 10 may be wound about a limb 11 in helical form, or it may be connected to said limb in any suitable manner. When the sockets depend 25 from the cord 10, as shown at the left hand end of Fig. 1, it will be seen that the casing 7 and the sockets will be held with their axes in substantially horizontal position. When the lamp, shown in dotted lines as 12, 30 is inserted in the socket and the reflector, shown in dotted lines as 13, is held in position on the socket the reflector will be in substantial vertical position so that the light from lamp 12 will be reflected forwardly. 35 The sockets which are disposed at the edge of the tree or adjacent the ends of the limbs can readily be positioned by merely having the loop formed by cord 10 and the conductors 8 and 9 extend over the end of the limb 11. This forms a very convenient 40 means of attachment and it is unnecessary to use a wire or other fastener to hold the sockets. When the sockets are so positioned, the same also will be disposed with their 45 axes in substantially horizontal position. With the conductors 8 and 9 thus projecting from the side of the sockets transversely of the axis thereof, it is seen that the sockets naturally hang in correct position and have 50 their reflectors properly positioned thereon. It will also be noted that the sockets can be suspended from a limb so as to hang into an open space on the tree so that a light can 55 be disposed in said open space and the 60 socket thereof will also have its axis in sub-

stantially horizontal position without any extra fastening or holding means. With the sockets of the prior art, it was often attempted to twist the conductors thereof about twigs or to secure the same by pieces 70 of wire in order to hold the sockets in horizontal position. This placed a strain on the conductors and often resulted in one of the conductors particularly the tip conductor, being pulled loose from the shell of the 75 socket. As Christmas tree sets are connected with the sockets in series, when one lamp would be rendered inoperative, the whole series is rendered inoperative. With the present construction, any twisting of the 80 conductors 8 and 9 about the limbs or twigs or any fasteners thereof by means of wires is avoided and yet the reflectors are disposed in the desired position. By having the passages 7^c and 7^d in casing 7 inclined, any 85 pull or strain occurring on conductors 8 and 9 is taken up largely by the walls of the casing 7 or said passages so that there is little stress placed on the contacts or connections with the tip and shell.

From the above description it is seen that applicant has provided a very simple and efficient lighting device and one which is a great improvement upon those of the prior art and constitutes a great advance in the 95 art. As above set forth, the device possesses many advantages and has a high degree of utility. The device has been amply demonstrated in actual practice and found to be 100 very successful and efficient.

It will, of course, be understood that various changes may be made in the form, details, arrangement and proportions of the parts without departing from the scope of applicant's invention, which, generally stated, consists in a device capable of carrying 105 out the objects above set forth, in the novel parts and combinations of parts disclosed and defined in the appended claims.

What is claimed is:

1. A lighting device comprising a socket for an electric lamp having a shell and a tip contact, a one-piece casing for said shell and a conductor for said shell extending into the side of said casing intermediate its ends transversely of the axis of said shell and inclined toward the open end thereof, and a conductor for said tip extending through said casing, both of said conductors lying in a plane extending from the axis of 115 said casing radially toward one side thereof.

2. A lighting device comprising a socket for an electric lamp having a metallic shell, a tip contact, a comparatively thick casing of insulating material to which said shell is 120 secured, and enclosing said shell and tip contact, and a pair of conductors connected respectively to said shell and tip contact 125 passing through said casing at points spaced longitudinally at the same side thereof.

whereby said socket may be suspended in horizontal position by both of said conductors.

3. A lighting device having in combination, a lamp socket comprising a shell and a tip contact, a casing of insulating material enclosing said shell and tip contact, a pair of conductors connected respectively to said shell and tip contact and extending through

one side of said casing in spaced relation, 10 and a cord to which the other ends of said conductors are connected, whereby a loop is formed which can be hung over the limb of a tree or other support with said sockets suspended with its axis substantially horizontal. 15

In testimony whereof I affix my signature.

LAMBERT L. RAYMOND.
